The ornamental design for a partitioned automated collection container, as shown and described.

DESCRIPTION

FIG. 1 is front perspective view of a partitioned automated collection container, with the lid closed, showing my new design;

FIG. 2 is a front elevational view thereof;

FIG. 3 is a rear elevational view thereof;

FIG. 4 is an elevational view of the right-hand side thereof;

FIG. 5 is an elevational view of the left-hand side thereof;

FIG. 6 is a top plan view thereof;

FIG. 7 is a bottom plan view thereof; and,

FIG. 8 is a front perspective view thereof, with one of the two lids fully open to disclose the upper portion of the partition separating the trash and recycling compartments.

FIG. 1.

FIG. 2.

FIG. 3.

FIG. 4.

FIG. 5.

FIG. 6.

FIG. 7.

FIG. 8.
